CLAIM

The ornamental design for a cable tray, substantially as shown and described.

DESCRIPTION

FIG. 1 is a perspective view of a cable tray showing our new design;

FIG. 2 is a side elevational view thereof, the opposite side being identical;

FIG. 3 is a front elevational view thereof, the rear view being identical; and

FIG. 4 is a top plan view thereof.

The rungs of the undisclosed bottom are U-shaped, with each leg of the U turned outwards at the top then downwards to form a snake-like sectional profile.

The rungs of the undisclosed bottom are substantially the same as that shown in FIG. 1.
